(57) **CLAIM**

The ornamental design for the sled for ice blocking, as shown and described.

DESCRIPTION

FIG. 1 is a perspective view of the sled for ice blocking affixed to an ice block shown in broken lines;

FIG. 2 is a perspective view of the sled for ice blocking affixed to a block of ice in use by a person for sledding down a grassy hill;

FIG. 3 is a perspective view of the sled for ice blocking;

FIG. 4 is a front elevation view of the sled for ice blocking;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines shown represent unclaimed subject matter and form no part of the claimed design.
